United States Patent Office

Des. 206,256
Patented Nov. 22, 1966

206,256

NOISE SUPPRESSING EAR MUFF

Charles J. Boyer, Reading, Pa., assignor to The Electric Storage Battery Company, Philadelphia, Pa.

Filed Feb. 21, 1966, Ser. No. 1,138

Term of patent 14 years

(Cl. D3—13)

Fig. 1.

Fig. 2.

Fig. 3.

FIG. 1 is a rear perspective view of a noise suppressing ear muff showing my new design;

FIG. 2 is a side perspective view thereof; and,

FIG. 3 is a top plan view.

I claim:

The ornamental design for a noise suppressing ear muff, substantially as shown.
